UNITED STATES PATENT OFFICE.

THOMAS WILLIAM DELANEY, OF ST. PAUL, MINNESOTA.

VALVE MECHANISM FOR ENGINES.

1,331,188.

Specification of Letters Patent.

Patented Feb. 17, 1920.

Application filed August 16, 1918. Serial No. 250,152.

To all whom it may concern:

Be it known that I, THOMAS WILLIAM DELANEY, a citizen of the United States, and a resident of St. Paul, in the county of Ramsey and State of Minnesota, have invented 5 a new and Improved Valve Mechanism for Engines, of which the following is a full, clear, and exact description.

This invention relates to prime movers, 10 and has particular reference to internal combustion or similar engines having reciprocating pistons, and hence while I show in this instance my improvement as applied to a revolving cylinder engine or one in which 15 a multiplicity of cylinders are connected to the same crank shaft and revolving around a stationary crank shaft, I wish it to be understood that in some of its aspects my improvement is adapted for use in other types 20 of engines than the one set forth in the drawings.

Among the specific objects, therefore, of 25 this invention is to provide an improved form of rotating or oscillating valve mechanism to control the admission and exhaust from the several cylinders.

A further object is to provide an improved cage or guide for a reciprocating puppet valve.

30 Further objects and advantages of the present construction will be outlined as this description progresses in connection with the accompanying two sheets of drawings of which—

35 Figure 1 is a vertical sectional view along the line of the crank shaft and indicating the principal parts of my engine.

Fig. 2 is a plan view of the upper part of 40 the structure shown in Fig. 1, namely the valve mechanism.

Fig. 3 is a vertical section on the line 3—3 of Fig. 4; and

Fig. 4 is a horizontal section on the line 4—4 of Fig. 3.

45 Referring now more specifically to the drawings and using reference characters so far as possible to represent similar parts of my general construction throughout a series of companion cases covering different parts 50 of the mechanism, for the convenience of every reader of the specification, 10 indicates a crank casing in or to the curved wall of which are secured a series of engine cylinders represented by the letters *a, d*. As suggested in Fig. 1 the cylinders of the series 55 are arranged in two parallel planes so that

the pistons are connected to two separate wrist pins 11 and 12 constituting parts of the same stationary crank shaft 13 suitably supported at one side of the engine upon 60 a stationary support 13' while the driven shaft 28 connected to the other side of the engine and driven as a result of the rotation of the crank casing is supported on a fixed support 30. At one side of the crank casing, 65 preferably adjacent to the standard or support 13', I provide an annular manifold 51 adapted to receive a supply of hydrocarbon fuel or the like from any suitably disposed carburetor, not shown, and from which an 70 inlet pipe 52 leads to each of the several cylinders. The several pipes 52 all lead from the central hub having a flange 53 over which projects a ring 53' making a substantially gas tight connection between the relatively stationary and rotatable parts of the manifold. 75

As set forth in another application wherein the specific construction of the cylinders is claimed, each cylinder is preferably 80 formed of sheet metal and in two parts connected in a plane perpendicular to the axis thereof in a flange 40 secured to or against the outer surface of the crank casing, while in the outer end of each cylinder and slightly 85 off the center thereof is fitted my improved valve mechanism to which particular attention is asked in this specification. This mechanism includes a stationary cage 54 having on its inner end an outwardly projecting flange 55 fitted upwardly against the end 56 of the cylinder and having a beveled valve seat 57 for the puppet valve 58. Said cage just outside of the flange 55 is enlarged 90 and is provided with screw threads 59 for the attachment of a stationary sleeve 60 which like the cage in general is of cylindrical form. The inner end of the sleeve is provided with an inwardly projecting rim having coöperating threads for attaching the 95 sleeve and cage together and binding the same against the opposite faces of the end portion 56 of the cylinder. Between the main portions of the sleeve and cage is a hollow cylindrical space in which is fitted an 100 oscillating shell 61 having an extension 62. The stationary parts 54 and 60 are provided with radially alined pairs of slots 63 and 64 respectively having ample capacity to provide quick admission and succeeding 105 exhaust. The shell 61 is provided with two sets of slots 65 and 66, the slots of each set 110

being adapted to register in alternation with the aforesaid slots 63 and 64. As shown in Fig. 4 the valve shell is adjusted for admission of an explosive charge, the slots 65 being in registry and hence open with those slots 63 and 64 within the adjacent end of the manifold inlet 52. On the other side, however, the slots 66 are closed. The construction of the valve cage and associated parts is such that a very slight oscillation of the shell is sufficient to give ample clearance for the inlet and discharge.

The outer end of the cage is provided with an inwardly projecting cup 67 having a tubular hub 68 constituting a guideway for the stem 69 of the puppet valve and having a head 70 on its outer end. Surrounding the hub 68 and bearing against the bottom of the cup and the head is a coil spring 71 whose function it is to close the puppet valve. This construction of cage provides for the least amount of dead space in the head of the engine cylinder, while at the same time there is provided free clearance for the movement of the gases. The cage and any other of the associated parts are preferably constructed of some suitable non-corrodible metal to increase the efficiency and reliability of the engine.

30 The spark plug is indicated at 72 and located in the side of the head 56 from which the valve mechanism is offset, and between the spark plug and the sleeve 60 is located a deflector 73 serving to prevent the exhaust gases from contaminating the spark plug or interfering with its operation. Any suitable means may be provided to actuate the movable parts of the valve mechanism, but as indicated herein such devices include a 40 cam sleeve 50 journaled for rotation around the crank shaft at one half the speed of the crank casing by means of gearing including a gear 74 fixed to the crank shaft and meshing with a gear 75 of the same size and carried in a ring 76. From the gear 75 is operated a pinion 77 meshing with a larger gear 78 fixed to the cam sleeve, the construction of which is more specifically set forth in a pending application. The cam sleeve is 45 provided with several sets of cams or projections which during the operation of the sleeve serve to actuate the several valve devices through the system of push rods and levers. A lever 79 pivoted at 80 bears at 50 one end against the head 70 of the puppet valve and to its other end is pivoted at 81 a push rod 82 slidable through a stuffing box 83 in the wall of the cam casing 84. The inner end of the push rod is secured to a slide 85 carrying an anti-friction roller 86 for co-operation with one of the cams on the cam sleeve.

Another push rod 87 reciprocates through a stuffing box 88 and is secured at its inner end to a slide 89 carrying a roller 90 for co-

operation with another of the cams. The outer end of the push rod 87 bears outwardly against the end 91 of a bell crank lever 92 pivoted at 93 to any suitable bracket and to whose opposite end 94 is pivoted a link 95 attached to the shell extension 62 at the point 96. A spring 97 tends to hold the extension 62 drawn toward the right as viewed in Figs. 1 and 2 and with the inlet ports open through the slots 64, 65, and 63. At 75 each movement of the roller 90 over a cam, however, the bell crank will be oscillated toward the left around its pivot 93, and the valve shell 61 will be given an oscillation in a clockwise direction in Fig. 1 closing the 80 ports 65 and opening the ports 66.

I claim:

1. The combination with an engine cylinder, having an opening in its end or head, of a valve cage of cylindrical form fitting 85 the said opening and having an annular flange at its inner end, said cage having external screw threads at its lower portion, a cylindrical sleeve around the cage having an internally screw-threaded lower end 90 engaging the threads of the cage and clamping the head between the end of the sleeve and the flange of the cage, said cage and sleeve being spaced apart forming an annular shell valve chamber, a valve in said chamber, said 95 sleeve and cage having registering ports therein, and said valve having ports therein adapted to be moved into and out of register with the ports in the cage and sleeve.

2. The combination with an engine cylinder 100 having an end flange or head and a circular hole formed therethrough at one side of its center and a spark plug fitted in the side of the head from which the hole is offset, of a valve cage of hollow cylindrical 105 form fitted in the head hole, a sleeve spaced from the main portion of the cage and serving as a means to lock the cage in place, said cage and sleeve having pairs of radially aligned slots, a shell of cylindrical form fitted 110 in the space between the cage and the sleeve and provided with two sets of slots, the sets being adapted to register in alternation with the slots aforesaid, means to move the shell to effect such alternate registration, and 115 means between the spark plug and the cage to deflect the exhaust gases from the spark plug.

3. The combination with an engine cylinder, having an opening in its end or head, 120 of a valve cage of cylindrical form fitting the said opening and having an annular flange at its inner end, said cage having external screw threads at its lower portion, a cylindrical sleeve around the cage having 125 an internally screw-threaded lower end engaging the threads of the cage and clamping the head between the end of the sleeve and the flange of the cage, said cage and sleeve being spaced apart forming an annular shell 130

valve chamber, a valve in said chamber, said sleeve and cage having registering ports therein, and said valve having ports therein adapted to be moved into and out of register 5 with the ports in the cage and sleeve, the outer end of the cage comprising an inwardly projecting cup formed with a central tubular outwardly projecting hub, a puppet

valve having a stem slidably fitted in the tubular hub and coöperating with the inner 10 end of the cage as a valve seat, and a spring surrounding said hub and seated in the bottom of the cup and bearing outwardly upon the puppet valve tending to close it.

THOMAS WILLIAM DELANEY.
